ANTENNA SYSTEM

Oakley M. Woodward, Jr., Princeton, N. J., assignor to Radio Corporation of America, a corporation of Delaware

Application February 22, 1945, Serial No. 579,177

7 Claims. (Cl. 250—33)

1

This invention relates to antenna systems, and more particularly to improved supporting and feed means for the radiator elements thereof.

The principal object of the present invention is to provide an improved radiator structure incorporating the feed connections in such manner that the radiator itself acts as a protective cover for the connections, so that no energized conductor is exposed to the weather except the radiator.

Another object is to provide a radiator structure of the described type in which a coaxial feed line acts as a partial or sole support for the radiator.

A further object is to provide a structure of the described type incorporating a coaxial line transformer in the connection between the feed line and the radiator.

These and other objects will become apparent to those skilled in the art upon consideration of the following description, with reference to the accompanying drawing, of which

Figure 1 is a sectional elevation of a stub-supported radiator according to prior art.

Figure 2 is a sectional elevation of a line-supported radiator in accordance with the instant invention.

Figure 3 is a sectional elevation of a modification of Figure 2, showing application of the invention to an antenna of the dipole type.

Figure 4 is a sectional elevation of a further modification of the structure of Figure 2, and

Figure 5 is a schematic diagram of an approximate equivalent circuit corresponding to the structure of Figure 4.

With the advent of extensive use of frequencies of fifty megacycles and higher for communication, and television picture transmission, it has become common practice to employ antennas in which the individual radiator elements have cross sectional dimensions which are a relatively large fraction of a wavelength. Such radiators are frequently made in the form of a hollow cylindrical tube supported on a parallel resonant line section, with the inner surface of the radiator acting as the outer conductor of the supporting line.

Referring to Figure 1, a representative prior art structure includes a tubular radiator 1, closed at its upper end by a disc 3, and supported by a rod 5 which is secured at its upper end to the disc 3 and at its lower end to a conductive member 7. The member 7 may be a mast, a conductive screen or reflector, a metal-clad outer wall of a building or the like. An insulator 9 surrounds the

2

rod 5 and engages the tubular member 1 near its lower end to maintain the parts in alignment.

The portion of the rod 5 which is surrounded by the tube 1 is approximately one-quarter wavelength long at the mean operating frequency. The members 1 and 5 cooperate to act as a quarter wavelength coaxial line, short-circuited at its upper end by the disc 3. This causes a substantially infinite impedance to appear between the lower end of the tube 1 and the rod 5, effectively insulating the radiator from the member 7.

The radiator is connected to a feed line 11 at its lower end by a conductor 13. The line 11 is of the coaxial type, and is provided with an end seal insulator 15. The insulator 15 serves to prevent the entrance of moisture and dirt into the line 11, and in some cases to retain gas in the feed system.

Referring to Figure 2, the rod 5 is omitted and the line 11 is extended within the radiator 1, which is supported on the line 11 by means of insulating discs 9 and 17. The inner conductor of the line 11 is connected to the end closure disc 3. By this arrangement, the end of the line 11 is protected from weather by the radiator itself, and the feed line performs the additional function of supporting the radiator.

The operation of the device of Figure 2 is somewhat different from that of Figure 1. The outer conductor of the feed line 11 cooperates with the inner surface of the radiator 1 to act as a coaxial line section, connected between the output end 16 of the line 11 and the lower end 18 of the radiator 1. Denoting the impedance between the lower end 18 of the radiator and ground as Z_{out} , and the impedance presented to the upper end 16 of the feed line 11 as Z_{in} ,

$$Z_{in} = Z_c \frac{Z_{out} + jZ_c \tan \rho}{Z_c + jZ_{out} \tan \rho}$$

where Z_c is the characteristic impedance of the line section formed by the outside of the line 11 and the inside of the radiator 1, and ρ is the electrical length of the said line section.

$$\rho = 2\pi \frac{b}{\lambda}$$

where

$$\frac{b}{\lambda}$$

is the length of the line section in wavelengths.

It will be apparent that the above-described line section operates as a transformer, converting the antenna impedance Z_{out} to a value Z_{in} . By

proper selection of the characteristic impedance Z_c and the electrical length ρ , Z_{in} may be made of any desired value for any specific value of Z_{out} . Thus the radiator may be matched to the line 11 without the use of separate transformers or matching stubs.

In some instances it may be desirable for ρ to be such that b is in effect greater than l , the length of the radiator 1. This condition can be met by filling the entire space between the line 11 and the radiator element 1 with dielectric material. The electrical length is then

$$\rho' = 2\pi \frac{b}{\lambda} \sqrt{k}$$

where k is the dielectric constant of the material. The parameter Z_c is also a function of k , as well as the ratio

$$\frac{d_1}{d_2}$$

of the inside diameter d_1 of the radiator 1 to the outside diameter d_2 of the line 11. The ratio

$$\frac{d_1}{d_2}$$

may be determined independently of the other characteristics of the system by adjustment of the wall thicknesses of the radiator 1 and the outer conductor of the line 11.

The electrical length ρ may be made less than that corresponding to the radiator length l by connecting the line to a disc 3' within the radiator 1, rather than at the outer end, as illustrated in Figure 3. Figure 3 also shows application of the present invention to a dipole structure, comprising a pair of opposed radiators 1 supported on their respective feed lines 11 extending radially of a mast 107. It will be apparent without further illustration that a plurality of such structures can be arranged to form an array, such as a turnstile antenna, and that the arrangement of Figure 2 may be substituted for the radiators of Figure 3 if a greater value of ρ is required.

Figure 4 shows a further modification in which series reactance may be provided at the feed point 10 or at the output end of the feed line 11, or both. An annular tubular portion 19 is provided within the lower radiator 1 and is connected thereto by a ring 21 at its upper end. The lower end remains open. The member 19 cooperates with the inner surface of the radiator 1 to function as a short-circuited coaxial line section of length D . This line section represents a reactance X_d in series with the radiator at the output end of the line transformer formed by the radiator 1 and the outside of the line 11. Referring to Figure 5, the approximate equivalent circuit of the structure of Figure 4 comprises the antenna impedance Z_a , connected in series with the reactance X_d to the output of the line transformer T . The value and sign of the reactance X_d is determined by the length D and the characteristic impedance Z_0 of the short-circuited line formed by the member 19.

In similar fashion a reactance X_g may be inserted in series with the input end of the line transformer T by providing an annular conductor 23 at the upper end of the line 11, short-circuited thereto by a ring 25. The value of X_g is determined by the length g of the member 23, and the ratio of the diameter of the member 23 to that of the outer conductor of the line 11.

The invention has been described as an improved radiator structure, wherein a coaxial feed

line is arranged to serve the additional function of supporting the radiator. The feed line extends coaxially within a tubular radiator, and is connected thereto at or near the outer end. The inner surface of the radiator cooperates with the outer surface of the feed line to provide a transformer action which is useful in matching the radiator to the line.

I claim as my invention:

1. An antenna system including at least one radiator including a substantially cylindrical tubular conductive member, a disc connected to and forming a closure within said tubular member and a coaxial line having an inner conductor and an outer sheath extending concentrically into said member and terminating near said disc, the inner conductor only of said line being connected to said disc and a series reactance in said system including an annular conductor between said tubular member and the outer sheath member of said line, said annular conductor being connected to one of said members at one end and free of both members at the other end.

2. An antenna system including at least one radiating element in the form of a conductive tubular member, a conductive disc member arranged transversely of said tubular conductive member and having the periphery thereof electrically connected to said conductive tubular member, a coaxial transmission line comprising an inner conductor and a sheath extending into said conductive tubular member and terminating near said disc member, the inner conductor only being connected to said disc member, and a tubular conductor arranged internally of said conductive tubular member and externally of said sheath, said tubular conductor having one end thereof connected to said tubular conductive member, thereby to interpose series reactance in said system.

3. An antenna system including at least one radiating element in the form of a conductive tubular member, a conductive disc member connected to said tubular conductive member and forming a closure within said conductive tubular member, a coaxial transmission line comprising an inner conductor and a sheath extending into said conductive tubular member and terminating near said disc member, the inner conductor only being connected to said disc member, and a tubular conductor arranged internally of said conductive tubular member and externally of said sheath, said tubular conductor having one end thereof connected to the sheath of said coaxial transmission line, thereby to interpose series reactance in said system.

4. An antenna system including at least one radiating element in the form of a cylindrical tubular conductive member, a conductive disc arranged transversely of said tubular conductive member and having the periphery thereof in conductive relationship with said tubular conductive member, a concentric transmission line comprising inner and outer conductors extending into said tubular member and terminating near said disc, the inner conductor only being connected to said disc, and tubular conductors arranged internally of said tubular member and externally of said outer conductor, one of said tubular conductors having one end thereof connected to said tubular conductive member and the other having one end thereof connected to said outer conductor, thereby to interpose series reactance in said system.

5. An antenna system including at least one

radiating element in the form of a cylindrical tubular conductive member, a conductive disc arranged transversely of said tubular conductive member and having the periphery thereof in conductive relationship with said tubular conductive member, a concentric transmission line comprising inner and outer conductors extending into said tubular member and terminating near said disc, the inner conductor only being connected to said disc, and tubular conductors arranged internally of said tubular member and externally of said outer conductors, one of said tubular conductors being arranged at one end of said tubular conductive member and connected thereto and the other tubular conductor being arranged at the innermost end of and connected to said outer conductor, thereby to interpose series reactance in said system.

6. An antenna system including at least one radiating element in the form of a tubular member of conductive material, a concentric transmission line element comprising an inner conductor and a shielding member extending into and terminating within said tubular member, the inner conductor only being connected to the interior of said tubular member, and a tubular conductor entirely within said tubular member and coaxially arranged between said members, said tubular conductor having one end thereof connected to one of said members and free of both of said members at the other end, thereby to interpose series reactance in said system.

7. An antenna system including at least one radiating element in the form of a tubular member of conductive material, a concentric transmission line element comprising an inner con-

5
10

ductor and a shielding member extending into and terminating within said tubular member, the inner conductor only being connected to the interior of said tubular member, and a tubular conductor completely contained by said tubular member and coaxially arranged between said members, said tubular conductor having one end thereof connected to one of said members at the end of said tubular conductor remote from the end of said one member and free of both of said members at the other end, thereby to interpose series reactance in said system.
